RUPTURE PAD COVER

Elias C. Bishelany, Brooklyn, N. Y.

Application September 28, 1935, Serial No. 42,631

1 Claim. (Cl. 128—95)

The main object of this invention is the provision of a novel attachment for the pads of rupture trusses, whereby the pad may be made more adaptable and useful in its function of pressing inward the portion of the abdomen at which the rupture occurs.

The common type of rupture truss pad is relatively large with a rounded contacting surface of relatively large area. In the case of most ruptures, the area against which the pressure of the pad is desired is small compared to the area of the pad. The result of using the common large pad is, therefore, that there is insufficient pressure against the ruptured area, and excessive pressure against the surrounding area, thus resulting in insufficient protection and support and in discomfort to the wearer of the truss. By means of this invention, any such common type of truss pad may be quickly equipped with an auxiliary pad of smaller area, and this auxiliary pad with the cover by means of which it may be mounted on the pad, is simple in construction and in mode of application, and also inexpensive in cost of manufacture.

The above and other objects will become apparent in the description below, in which characters of reference refer to like-named parts in the accompanying drawing.

Referring briefly to the drawing, Figure 1 is a side view, partly in section, of a common truss pad having the auxiliary pad mounted thereon.

Figure 2 is a cross-sectional view taken on the line 2—2 of Figure 1.

Figure 3 is a bottom plan view of Figure 1.

Figure 4 is a perspective view of the auxiliary pad and its attaching cover per se.

Applicant is aware that the idea of a smaller auxiliary pad mounted on the larger truss pad, is not new. Such truss pads which possess this feature, however, have the auxiliary pad permanently connected and built on at the factory. But most of the trusses on the market today do not possess any smaller auxiliary pad, and the device of this invention aims to provide an auxiliary pad of this type which may be slipped on the larger truss pad by anyone who is in possession of this common type of truss pad, that is, the type which does not embody the auxiliary pad.

Referring in detail to the drawing, the numeral 10 represents the common type of truss pad which is usually made of rubber or other resilient material covered with a layer of silk or cloth 11. The upper surface of the pad (Figures 1 and 2) is provided with the usual means (not shown) for securing it to the truss or belt (not shown).

The auxiliary pad comprises a body of rubber or other suitable material formed after the fashion of a turtle-back-shaped button 12 having the hollow space 13 contained between the same and the truss pad 10 when mounted in position. A rubber cover 14, preferably made of a single sheet of material, is so formed that it fits snugly over the button 12, the body 10 of the truss pad, and is beaded or otherwise stiffened around the line 15 which fits against the base of the button 12 on the pad 10. Straps 16 are provided to retain the cover 14 tightly against the pad 10. That portion of the cover 14 which surrounds the button 12 is preferably glued to the button, or the button may even be formed integral therewith.

The manner in which the auxiliary pad or button 12 may be readily slipped on or off the truss pad 10, is obvious. In use, the air cushion provided under the button 12 offers a gentler pressure than is the case in which the button is made of solid rubber. Obviously, modifications may be made without departing from the spirit of the invention as set forth.

I claim:

A snap-on auxiliary button for a rupture truss pad comprising a cover of resilient material adapted to be mounted on the truss pad, said button being hollow and adapted to be mounted on said truss pad with the periphery of said button lying in contact with the surface of said truss pad, said cover having a convex elevation formed therein intermediate one side of said pad, the convex surface of said button being affixed to the underside of said elevation and registering therein between said pad and said cover, and endless bands formed integral with said cover adapted to encircle the back of said truss pad for releasably securing said cover and button to said truss pad.

ELIAS CH. BISHELANY.
